UNITED STATES PATENT OFFICE.

FRANK C. HOEBS, OF BUFFALO, NEW YORK.

AUTOMATIC STOP FOR SOUND-REPRODUCTION APPARATUS.

Application filed December 23, 1921. Serial No. 524,386.

To all whom it may concern:

Be it known that I, FRANK C. HOEBS, a citizen of the United States, residing at Buffalo, in the county of Erie and State of New York, have invented certain new and useful Improvements in Automatic Stops for Sound-Reproduction Apparatus, of which the following is a specification.

This invention relates to improvements in automatic stops for sound reproduction apparatus.

One of the objects of the present invention is to provide a stop which will require no attention in setting it for operation but which will be automatically set upon movement of the tone arm in substantially the usual manner after the record has been placed upon the record supporting turntable.

Another object of the invention is to provide an automatic stop which will operate automatically to arrest the motion of the turntable when the inner end of the record groove has been reached by the stylus of the reproducer regardless of the length of the record so that it is unnecessary to make adjustments to compensate for variations in the lengths of records being reproduced.

Another object of the invention is to provide an automatic stop for sound reproduction apparatus which will be positive in its action, simple in construction, and not liable to disarrangement of its parts.

In the accompanying drawings:

Figure 1 is a plan view of the stop mechanism embodying the invention;

Figure 2 is a vertical sectional view in detail taken substantially on the line 2—2 of Figure 1 looking in the direction indicated by the arrows;

Figure 3 is a side elevation of the mechanism;

Figure 4 is a group perspective view illustrating the carrier plate, brake lever, detent, and associated parts of the mechanism;

Figure 5 is a perspective view of the supporting base plate of the mechanism;

Figure 6 is a perspective view illustrating the setting lever and the trip finger which is carried by the tone arm of the apparatus;

Figure 7 is a transverse sectional view on the line 7—7 of Figure 1 looking in the direction indicated by the arrows;

Figure 8 is a similar view on the line 8—8 of Figure 1 looking in the direction indicated by the arrows;

Figure 9 is a detail transverse sectional view through one end of the detent.

In the drawings the numeral 1 indicates in general the record supporting turntable of the apparatus which is driven by any suitable type of motor through the medium of the usual spindle indicated by the numeral 2. The tone arm is indicated by the numeral 3 and is of the ordinary construction and supports the reproducer 4 and its neck 5 which is swiveled to the tone arm in the usual manner. The turn table 1 is provided with the usual flange 6 at its periphery against which flange braking action is to be exerted when the apparatus is not in actual operation. The mechanism embodying the invention is supported practically in its entirety upon a supporting base plate which is best shown in Figure 5 of the drawings and which is indicated in general by the numeral 7. The base plate 7 is of frame-like structure and is secured upon the top board of the cabinet of the apparatus. The said base plate, for purposes to be presently explained, is formed with spaced upstanding flanges 8 and 9 which constitute guides and tracks for supporting and guiding the carrier plate of the mechanism, and the said base plate is also provided with an upstanding flange 10 which serves a similar purpose, the flanges 8, 9 and 10 being arcuate and concentric with relation to one another. The base plate is also formed with a supporting flange 11 and a supporting and guiding flange 12 for the setting lever of the mechanism, the latter flange being provided with a slot 13. The base plate is also formed with upstanding guiding and supporting flanges 14 and 15 for the brake lever, the latter flange being provided with a slot 16 the purpose of which will presently be explained.

The carrier plate heretofore referred to is indicated in general by the numeral 17 and the said plate is disposed upon the upper edges of the flanges 8, 9 and 10 and thus supported for shifting movement above the base plate 7. In order to guide the plate 17, it is provided upon its under side with pairs of rollers 18 and 19 which, as best shown in Figure 2, travel respectively against the inner sides of the flanges 8 and 9. In order to restrain the carrier plate 17 against upward displacement, the said plate is provided at what may be termed its inner end as it is the end which is located nearer the center about which the flanges 8, 9 and

10 are concentric, with a lip 20 which projects beneath a guide 21 secured at its ends upon the upper side of the base plate 7 and having its intermediate portions spaced from said plate, this construction being clearly shown in Figure 2 of the drawings.

The brake lever of the mechanism is indicated in general by the numeral 22 and the same is pivotally supported at one end as 10 at 23 upon the base plate 7, the said lever being formed near its other end with a longitudinally extending slot 24. Near its pivoted end the brake lever is provided with an upstanding clamp 25 supporting a brake shoe 15 26 of leather or other suitable friction material which is presented toward the inner side of the flange 6 of the record supporting turntable and is designed to be brought into braking engagement with said flange when 20 the brake lever 22 is swung in one direction upon its pivot 23 and to be moved out of engagement with the flange when the lever is swung in the opposite direction. The slotted end of the brake lever 22 projects 25 over an extension 27 at the outer end of the carrier plate 17 and in order to effect movement of the brake lever into and out of braking positions, a thrust link 28 is provided and is slidably mounted upon the extension 30 27 of the carrier plate 17. This thrust link is provided at its outer end with a stud 29 which works in the slot 24 in the brake lever 22 and at its inner end is provided upon its under side with a boss 30 which rests slidably upon the upper side of the extension 27 of the said carrier plate. The carrier plate is provided along one longitudinal edge at that side at which the extension 27 is located, with an upstanding flange 31 which serves a 35 purpose to be presently pointed out and which is formed with a longitudinal slot 32 slidably receiving a lug 33 which projects from one end of the boss 30 and which is notched as indicated by the numeral 34. A 40 tension spring 35 is engaged at one end in the notch 34 of the lug 33 and at its other end is engaged with a lug 36 which projects laterally from the outer end of the flange 31 of the carrier plate. It will now be evident 45 that the spring 35 normally tends to exert a pull upon the thrust link 28 to shift the same outwardly longitudinally upon the extension 27 of the carrier plate and that when such movement of the link 28 is permitted, the brake lever 22 will be swung upon its 50 pivot 23 to bring the brake shoe 26 into engagement with the braking flange of the record supporting turntable. Movement of the thrust link 28 in the opposite direction 55 and against the tension of the spring 35 will serve of course to so swing the lever 22 upon its pivot as to move the brake shoe 26 out of braking engagement with the flange 6 thus releasing the turntable for rotation 60 through the medium of its driving motor.

It is of course essential that the brake lever 22 be held in inactive position while the record is being reproduced, and with this end in view there is provided, in connection with the thrust link 28, a detent which is indicated in general by the numeral 37. The detent 37 is pivotally mounted by means of a pivot screw 38 upon the under side of the extension 27 of the carrier plate 17 and the said detent is provided at one end with a shoulder 39 which is adapted to engage and coact with the flattened side 40 of a stud 41 which is fixed at the inner end of the thrust link 28 adjacent to the boss 30, the stud 41 projecting downwardly from the link 28 and working through a slot 42 formed in the extension 27 of the carrier plate 17. It will now be evident that when the brake lever 22 is in inactive position, the thrust link 28 will be shifted inwardly against the tension of the spring 35, the shoulder 39 of the detent 37 will engage behind the flattened side 40 of the stud 41 as shown in Figure 2 of the drawings thus holding the link 28 shifted inwardly and maintaining the brake lever 22 in inactive position. However with the parts in this position the spring 35 will be under tension and it will therefore be evident that when the detent 37 is swung upon its pivot, the shoulder 39 will be brought out of engagement with the flattened side 40 of the stud 41 and the link 28 will be released for shifting movement under the influence of the spring to thus move the brake lever 22 to active position. The detent 37 is normally held in position for the coaction of its shoulder 39 with the stud 41 by means of a spring 43 coiled at an intermediate point about the pivot pin 38 and anchored at one end as at 44 in the extension 27 of the carrier plate 17, the other end of the spring engaging in a groove 45 formed in the edge of the detent 37 at that end at which the shoulder 39 is located. By reference to Figure 2 of the drawings it will be observed that the detent 37 is mounted upon the under side of the extension 27 and that the lower end of the stud 41 projects below the plane of the under side of the said extension 27 in position for engagement by the shoulder 39.

Movement of the thrust link 28 inwardly to move the brake lever 22 to inactive position is effected through the medium of a setting lever which is indicated in general by the numeral 46. The setting lever 46 is pivotally mounted as at 47, between its ends, upon a raised portion 48 of the base plate 7 and at one end the lever is supported upon the flange 11 and at its other end it works through the slot 13 in the flange 12. The last mentioned end of the lever is provided with a finger 49 which projects between the extension 27 of the carrier plate 17 and the thrust link 28 and, when the lever is rocked in one direction, engages the lower end por-

tion of the stud 41 and moves the thrust link longitudinally inwardly until the stud engages behind the shoulder 39 of the detent 37. This movement of the lever 46 is effected through the medium of a trip arm which is carried by the tone arm of the apparatus and which is indicated in general by the numeral 50. The arm 50 is provided with a rounded outer engaging end 51 designed to ride against a cam projection 52 upon that end of the setting lever 46 opposite the end which carries the finger 49, the arm 50 moving in an arc with the tone arm, and the cam projection 52 being located in the path of movement of the outer end 51 of the said arm 50.

The trip arm 50 is provided near its inner end with an upturned portion 53 which is secured in any suitable manner as at 54 to the under side of the tone arm 3, the said portion 53 being preferably provided with a lateral extension projecting beyond the tone arm and indicated by the numeral 55 to afford a support for the reproducer when the reproducer is swung back to inactive position. For a purpose to be presently explained the trip arm 50 is formed with a slot 56 located near its outer engaging end 51, and it is also formed upon its under side, inwardly of the slot 56, with a lug 57. In the inward swinging movement of the tone arm 3, the corresponding movement of the trip arm 50 will bring one longitudinal edge of this latter arm into engagement against the inner side of the upstanding flange 31 of the carrier plate 17 so that the said plate will be picked up and carried over the flanges 8, 9 and 10 in consonance with the movement of the tone and trip arms. When the trip arm 50 engages against the flange 31, its slot 56 will be brought into registration with a slot 58 formed in the said carrier plate. The numeral 59 indicates in general a latch comprising a resilient shank 60 secured as at 61 to the under side of the carrier plate 17 and provided at its free end with an upstanding latch head 62 which projects through the slot 58 and engages in the slot 56 in the trip arm 50 thus locking the trip arm 50 with relation to the carrier plate 17 so that these parts will move in unison. It will now be evident that when the tone arm 3 is moved inwardly, the edge of the trip arm 50 will be brought into engagement with the flange 31 of the carrier plate 17 and as the arm 3 continues to move inwardly, the carrier plate will be correspondingly moved. Inasmuch as in this position of the parts the latch head 62 will lock together the trip arm 50 and carrier plate, it is evident that the outward swinging movement of the tone arm will effect a corresponding movement of the carrier plate and the return of the latter to its normal position of shifting movement. However it is necessary that the parts be

disengaged or in other words that the trip arm be released from engagement with the carrier plate 17, when the carrier plate has reached the limit of its movement to normal position, and the means employed for this purpose comprises a finger 63 provided near one end with a slot 64 receiving an upstanding stud 65 upon the base plate 7 and a set screw 66 which is threaded into said plate. The engagement of the stud and set screw 66 through the slot 64 serves to prevent any pivotal displacement of the finger 63 and at the same time, by loosening the set screw 66, the finger may be adjusted in the direction of its length. The finger projects between the flanges 8 and 9 and has its free end portion deflected in an upward direction as indicated by the numeral 67 and gradually thinned to a relatively sharp extremity. The portion 68 of the finger rests against the under side of the carrier plate 17 and the finger is located in the path of movement of the latch 59 so that when the tone arm is swung outwardly and the carrier plate is shifted in a corresponding direction, the parts being at such time locked together by the latch head 62, the stem 60 of the latch 59 will ride against and beneath the extremity 68 of the finger 63, and the latch 59 will be sprung downwardly to disengage its head 62 from the slots 56 and 58, thus releasing the trip arm and permitting continued movement of the same in unison with the tone arm while the carrier plate remains stationary in the position to which it has been moved. In order to assist the trip arm 50 in bringing the carrier plate back to its normal position, a spring 69 is coiled between its ends as at 70 and secured to the under side of the carrier plate and has its end portions extending in opposite directions and slightly bowed at their extremities as at 71 for engagement against the ends of the flanges 8 and 9. It will be evident that when the carrier plate is moved through the medium of the trip arm, the intermediate portion of the spring 69 will be drawn with it and the ends 71 of the spring will ride in engagement with the said ends of the flanges, the spring being relieved, to a degree, of its tension when the carrier plate has reached its normal position, and serving also as a means for retaining the plate in this position until it is again engaged by the trip arm.

In order to steady the carrier plate 17 and to a certain extent take up the longitudinal thrust of said plate, the plate is preferably formed near its inner end with a recess 72 to receive the lug 57 upon the trip arm 50.

The mechanism further embodies a worm shaft which is indicated in general by the numeral 72' and which is mounted in suitable bearings 73 provided upon the base plate 7. A worm pinion 74 is fixed or

formed upon this shaft and meshes with a worm gear 75 rotatable with the supporting spindle 2 for the record supporting turntable. The threads of the worm shaft 72' are indicated by the numeral 76, and the 10 detent 37 supports at its outer end a nut 77 for co-action with the threads 76 of the worm shaft. The nut 77 comprises a rocker 78 pivotally mounted intermediate its ends upon the upper side of the said detent 37, and this rocker is provided at one end with a head 79 the engaging face of which is formed to mesh with the threads 76. A 15 roller 80 is mounted upon the other end of the rocker 78 and is designed to coact with the brake lever under conditions which will presently be explained, a spring 81 being provided for holding the nut 77 in engagement with the worm 76. One of the bearing 20 brackets for the worm shaft 72' is provided with a rest 82 for the head of the nut 77.

In Figure 1 of the drawings the parts are illustrated in the positions which they will occupy while the record is being reproduced except that the tone arm is to be moved inwardly and the stylus of the reproducer placed in the outer end of the record groove. As the tone arm is carried inwardly in the usual way, the edge of the trip arm 50 will 30 first be brought into engagement with the flange 31 of the carrier plate 17 and this plate will be moved along with the tone arm. As the carrier plate is moved in the direction stated, the latch 59 will disengage from 35 the finger 63 allowing the latch head 62 to be projected upwardly through the slots 58 and 56 thus connecting together the trip arm and carrier plate for movement in unison. The movement of the carrier plate 40 effects a disengagement of the head 79 of the nut 77 from the rest 82 so that the spring 81 will move the said head 79 into mesh with the worm 76 which is continuously rotating. The carrier plate will continue to 45 move in unison with the tone arm and trip arm until the stylus of the reproducer reaches the inner end of the record groove whereupon the tone arm will cease to move inwardly, but as the worm shaft 72' is rotating and the nut 77 is in mesh therewith, the 50 nut will be fed inwardly with the result that the detent 37 upon which it is carried will be rocked upon its pivot to disengage the shoulder 39 from the stud 41 thus releasing the thrust link 28 and permitting the 55 spring 35 to act to shift this link outwardly. This movement of the link serves to rock the brake lever 22 about its pivot to bring the brake shoe 26 into braking engagement 60 with the flange 6 of the record supporting turntable 1 thereby arresting the motion of this table. At the moment the brake lever 22 is rocked outwardly through the shifting of the thrust link 28, the edge of the lever 65 will be brought into engagement with the

roller 80 upon the nut 77 thus disengaging the head 79 of the nut from the threads 76 of the worm shaft. In order to reset the mechanism for the playing of another record, it is only necessary to swing the tone 70 arm 3 in an outward direction whereupon the engaging end of the trip arm 50 will ride against the cam portion 52 of the said setting lever 46 causing the lever to rock 75 upon its pivot and bring the finger 49 thereof into engagement with the stud 41 and thus shift the thrust link 28 longitudinally inwardly against the tension of the spring 35 until the stud rises past and engages behind the shoulder 39 of the detent 37 thus 80 the brake lever 22 will be moved to inactive position and the turntable will be released for a resumption of its rotation. Of course when the tone arm 3 is initially swung outwardly, the carrier plate 17 will be carried with it and the plate will be restored to its normal position as shown in Figure 1. However as the carrier plate assumes this position, the extremity 68 of the finger 63 will engage with the latch 59 in a manner to 85 spring the latch downwardly and withdraw its head 62 from engagement in the slot 56 in the trip arm so that the arm will then be disconnected from the carrier plate and the tone arm may be swung further in an outwardly direction without effecting any further movement of the carrier plate.

Having thus described the invention what is claimed as new is:

1. In sound reproduction apparatus including a record supporting turntable and a tone arm, means for automatically arresting the movement of the turntable upon completion of the period of reproduction comprising a brake member, a carrier movable through movement of the tone arm during the reproduction period, means carried by the carrier and coacting with the brake member tending to move the brake member to active position, a detent upon the carrier for restraining the last mentioned means when the latter is moved to inactive position, means operable through manual movement of the tone arm to move the said last mentioned means to inactive position and thereby render the brake inactive, and means operable through rotation of the turntable to effect movement of the detent to inactive position upon cessation of movement of the tone arm and carrier. 105

2. In sound reproduction apparatus including a record supporting turntable and a tone arm, means for automatically arresting the movement of the turntable upon completion of the period of reproduction comprising a brake member, a carrier movable with the tone arm during the period of reproduction, a thrust member upon the carrier operatively connected with the brake member, means tending to move the thrust 125 member, means for automatically arresting the movement of the turntable upon completion of the period of reproduction comprising a carrier movable with the tone arm during the period of reproduction, a thrust member upon the carrier operatively connected with the brake member, means tending to move the thrust 130

member in a direction to render the brake member active, a detent upon the carrier for coaction with the thrust member to restrain the same in inactive position, means for 5 moving the thrust member to inactive position and for engagement by the detent, and means actuated through rotation of the turntable subsequent to cessation of movement of the tone arm and carrier to render 10 the detent inactive.

3. In sound reproduction apparatus including a record supporting turntable and a tone arm, means for automatically arresting the movement of the turntable upon 15 completion of the period of reproduction comprising a brake member, a carrier movable with the tone arm during the period of reproduction, a thrust member upon the carrier operatively connected with the brake member, means tending to move the thrust member in a direction to render the brake member active, a detent upon the carrier for coaction with the thrust member to restrain the same in inactive position, means 20 for moving the thrust member to inactive position and for engagement by the detent, and means actuated through rotation of the turntable subsequent to cessation of movement of the tone arm and carrier to render 25 the detent inactive, the said means comprising a worm shaft rotated in consonance with the turntable, and an element upon the detent for coaction with the worm of the shaft.

35 4. In sound reproduction apparatus including a record supporting turntable and a tone arm, means for automatically arresting the movement of the turntable upon completion of the period of reproduction comprising 40 a brake member, a carrier movable with the tone arm during the period of reproduction, a thrust member upon the carrier operatively connected with the brake member, means tending to actuate the thrust member 45 to move the brake member to active position, means for moving the thrust member to inactive position, a detent upon the carrier for restraining the thrust member in inactive position, and means for rendering the detent 50 inactive upon cessation of movement of the tone arm comprising a worm shaft rotated in consonance with the turntable, a rocker upon the detent having means for operative engagement with the worm of the shaft, means tending to move the rocker to bring 55 its said means into coactive relation to the said worm, and means operable to automatically disengage the rocker from the worm upon movement of the brake member to active position.

60 5. In sound reproduction apparatus including a record supporting turntable and a tone arm, means for automatically arresting the movement of the turntable upon completion of the period of reproduction com-

prising a brake member, a carrier movable with the tone arm during the period of reproduction, a thrust member upon the carrier operatively connected with the brake member, means tending to actuate the thrust member to move the brake member to active position, means for moving the thrust member to inactive position, a detent upon the carrier for restraining the thrust member in inactive position, and means for rendering the detent inactive upon cessation of movement of the tone arm comprising a worm shaft rotated in consonance with the turntable, a rocker upon the detent having means for operative engagement with the worm of the shaft, means tending to move the rocker to bring its said means into coactive relation to the said worm, and means upon the rocker engageable by the brake member upon movement of the brake member to active position to disengage the rocker from the worm.

65 6. In sound reproduction apparatus including a record supporting turntable and a tone arm, means for automatically arresting the movement of the turntable upon completion of the period of reproduction comprising a brake member, a carrier movable with the tone arm during the period of reproduction, a thrust member upon the carrier operatively connected with the brake member, means tending to actuate the thrust member to move the brake member to active position, the said carrier having a slot, a stud upon 70 the thrust member projecting through said slot, a detent pivotally supported upon the carrier for restraining the thrust member in inactive position by coaction with the said stud, means actuated through manual movement of the tone arm to engage with the stud and shift the thrust member to inactive position, and means actuated through rotation of the turntable subsequent to cessation of movement of the tone arm to render the detent inactive.

75 7. In sound reproduction apparatus including a record supporting turntable and a tone arm, means for automatically arresting the movement of the turntable upon completion of the period of reproduction comprising a brake member, a carrier movable with the tone arm during the period of reproduction, a thrust member slidably mounted upon the carrier and operatively connected with the brake member, means tending to shift the thrust member in one direction to render the brake member active, a setting lever mounted for rocking movement and having means for coaction with an element of the thrust member to shift the thrust member in the opposite direction when the setting lever is rocked in one direction, coacting means upon the tone arm and setting lever for effecting such movement for the setting lever when the tone arm

is manually moved, a detent for restraining the thrust member when moved to position to render the brake member inactive, and means automatically operable to render the 5 detent inactive upon cessation of movement of the tone arm.

8. In sound reproduction apparatus including a record supporting turntable and a tone arm, means for automatically arresting 10 the movement of the turntable upon completion of the period of reproduction comprising a brake member, a carrier comprising a movably supported plate having an abutment, means upon the tone arm positioned 15 for engagement with said abutment when the tone arm is moved in one direction during the period of reproduction, means for automatically coupling the means upon the

tone arm and the said carrier whereby the carrier will be moved with the tone arm 20 when the tone arm is manually moved in the opposite direction, means operable to render the coupling means inactive when the carrier has reached its normal position in its movement in the last mentioned direction, 25 means upon the carrier operatively connected with the brake member and tending to move the brake member to active position, a detent for holding the brake-member-moving means in inactive position, and means for automatically rendering the said 30 detent inactive upon cessation of movement of the tone arm at the completion of the period of reproduction.

In testimony whereof I affix my signature.
FRANK C. HOBBS. [L. s.]
